UNITED STATES PATENT OFFICE.

WILLIAM N. BEST, OF NEW YORK, N. Y.

HEATING AND MELTING FURNACE.

1,119,227.

Specification of Letters Patent.

Patented Dec. 1, 1914.

Application filed June 24, 1914. Serial No. 846,922.

To all whom it may concern:

Be it known that I, WILLIAM N. BEST, a citizen of the United States, and resident of New York city, borough of Brooklyn, in the county of New York and State of New York, have invented certain new and useful Improvements in Heating and Melting Furnaces, of which the following is a specification.

10 This invention relates to certain improvements in furnaces and more particularly to that type in which a gaseous liquid, or pulverized fuel is employed to produce the desired high temperature and in which the 15 flame and the heated gases are delivered directly into the main heating chamber of the furnace. Furnaces of this general type may be employed for heating metal or other parts, melting metals or alloys, or for other 20 analogous purposes. Examples of such furnaces are shown in numerous of my prior patents such, for instance, as Patents 887,182 and 941,609.

The main object of my present invention 25 is to secure a higher and more uniform degree of heat throughout all parts of the heating furnace and to more effectively apply the heat to bodies or containers on the floor of the chamber. This I accomplish 30 partly by the novel form and the relative arrangement of the combustion and heating chambers and partly by the novel construction and arrangement of the flues for the exhaust gases.

35 In the accompanying drawings, I have illustrated one embodiment of my invention but it will be evident that various changes may be made in the details of construction and arrangement of the parts, within the 40 spirit of my invention, and without departing from the scope of the appended claims. Therefore I desire the drawings to be considered merely as illustrative of my invention and not as limiting it.

45 In these drawings in which similar reference characters indicate corresponding parts in the several views:—Figure 1, is a top plan view of the body of a furnace constructed in accordance with my invention, 50 the fuel, air, and exhaust conduits being removed. Fig. 2, is a horizontal section through the combustion and heating chambers, said section being taken substantially on the line 2—2 of Fig. 3. Fig. 3, is a vertical longitudinal section taken on the line 55 3—3 of Fig. 2. Fig. 4, is a vertical trans-

verse section on the line 4—4 of Fig. 3. Fig. 5 is a section similar to a portion of Fig. 4, but showing checkerwork between the combustion and heating chambers, and, 60 Fig. 6 is a section similar to a portion of Fig. 2, but showing the checkerwork of Fig. 5.

The walls of the furnace may be formed of any suitable refractory material and may 65 be made up either of separate blocks or bricks or may be monolithic. As shown it is formed of blocks held together by metal binding and reinforcing rods and bars. The furnace includes two main chambers 10 and 70 11, the former of which, constitutes the heating chamber and the latter the combustion chamber. The heating chamber is shown substantially rectangular in horizontal cross section with a floor 12 of any suitable material, although ordinarily I prefer to employ furnace sand. The ends of the main heating chamber may be closed by removable doors 13, and these preferably have 75 peep holes 14 through which the workman 80 may note the progress of the heating operations. Below each door, I may mount an air pipe 15, having a plurality of small openings through which air may be delivered in front of the door to protect the 85 workman from the excessive heat, particularly when the doors are opened.

The combustion chamber 11 is triangular in horizontal section, the apex of the triangle opening through the outer wall, and 90 the base of the triangle being of a width closely approximating the total length of the heating chamber and openly communicating therewith. The roof 16 of the combustion chamber is arched transversely and 95 the floor or lower wall 17 thereof is at a lower level at the inner end of the combustion chamber than at the outer. The roof 18 of the heating chamber is arched lengthwise of the heating chamber, in other words, 100 it is curved in a direction at right angles to a direction of curvature of the roof or top 16 of the combustion chamber. This roof 18 at one side abuts against the roof portion 16 so that in the vertical medial 105 plans of the furnace, the two roof sections are substantially in alinement. From this point the roof section 18 curves downwardly and is supported by the side wall 19 of the furnace along a line very much lower than 110 the roof of the combustion chamber and preferably substantially in the same hori-

horizontal plane as the bottom of the combustion chamber.

Beneath the combustion chamber, there are a plurality of exhaust gas outlets forming the ends of flues 20 extending substantially horizontally to a transverse flue 21. These flues 20 may be of any desired number, but are of sufficient capacity to permit the free escape of the gases of combustion from the heating chamber. The flue 21 lies beneath the narrower portion of the combustion chamber and from one or both ends thereof a vertical flue 22 extends upwardly to the top of the furnace. These extend along opposite sides of the combustion chamber, and may be united by a transverse conduit 23 above the combustion chamber and deliver to a single stack 23. This transverse conduit is preferably spaced above the top wall so that air may enter there-beneath and prevent the up-draft in the stack from sucking gas out of the heating chamber.

For heating the furnace, I preferably provide a burner 24 of a character designed for delivering a comparatively flat fan-shaped sheet of vaporized or atomized fuel from the apex of the triangular combustion chamber toward the base thereof. The fan-shaped sheet is preferably secured by the use of an atomizing fluid such for instance as compressed air or steam. Burners suitable for the purpose are shown in my prior patents 708,453 and 752,195. Below the burner 35 or atomizing nozzle, I provide a separate conduit 25 for delivering combustion-supporting air, preferably under pressure. The volume of air delivered may be controlled in accordance with the temperature desired 40 and to secure an oxidizing or reducing flame. A smaller volume of air is sufficient if compressed air be used as the atomizing fluid rather than steam.

In using my improved furnace, the articles to be heated or the crucibles or other containers for metals or alloys to be melted, are placed on the floor of the heating chamber and the proper supply of fuel and air delivered at the inlet to the combustion chamber. Substantially the entire combustion chamber will be filled with a sheet of flame which is delivered to the upper portion of the heating chamber. By reason of the particular shape and formation of the heating chamber, the flame and gases will be brought down directly on to the articles to be heated and will sweep across the upper portion and then back along the lower portion toward the flues 20. The flues 20 being arranged uniformly across the wall of the heating chamber beneath the combustion chamber, tend to withdraw equal portions of gas along the entire length of the heating chamber. It will be noted that the combustion chamber delivers a slightly greater

volume of flame and gases to the center portion of the heating chamber, but it will also be noted that the vertical flues 22 are closer to the end flues 20, than to the middle ones therefore the two tendencies counteract each other and produce a uniform distribution of flame and heated gases throughout the heating chamber. The forming of the heated chamber of a height much less at the side away from the combustion chamber than at the side adjacent the combustion chamber, insures almost perfect heat reverberation and aids materially in the production of the uniform temperature in all parts of the chamber. The placing of exhaust flues as described, not only causes the gas to properly flow back across the base or floor of the chamber, but the heated gas in passing through the flues heats up the walls, not only below, but at the sides of the combustion chamber, so as to conserve the heat produced in combustion chamber by the direct burning of the fuel and reduce the losses due to radiation.

It is of course evident that the size and proportions of the heating chamber may be varied somewhat in accordance with the character of the material to be heated. In case the furnace is employed for annealing, I preferably insert a checkerwork of brick 95 26 or other suitable material between the combustion chamber and the heating chamber so as to conserve the heat and to prevent the flames from playing directly on the articles to be annealed. One form of checker-work which may be employed for the purpose is illustrated in Figs. 5 and 6, where bricks are arranged so as to leave a large number of comparatively small passages for the hot gases.

Having thus described my invention, what I claim as new and desire to protect by Letters Patent, is:—

1. A furnace having a heating chamber provided with a floor, an end door and a roof substantially higher along one side than along the opposite side, a laterally flaring combustion chamber having an open flame delivering side extending along substantially the entire length of the first mentioned side of said heating chamber adjacent to said roof, a series of substantially horizontal flues having their inlet ends communicating with said heating chamber at spaced points along said first mentioned side of the latter above the bottom and directly below the flame delivering side of said combustion chamber, and a transverse flue below said combustion chamber and communicating with the delivering ends of said first mentioned flues and having an outlet at each end thereof.

2. A furnace having a heating chamber provided with a floor, an end door and a roof, a laterally flaring combustion chamber

- ber having an open flame delivering side extending along substantially the entire length of one side of said heating chamber adjacent to said roof, and a series of substantially 5 horizontal outlet flues beneath said combustion chamber and leading from said heating chamber at spaced points along said side of the latter and above the bottom and directly below the flame delivering side of said combustion chamber.
3. A furnace including a heating chamber, a laterally flaring combustion chamber communicating therewith along one side of said heating chamber, a fuel vaporizing jet 15 adapted to deliver a fan shaped film of vapor substantially entirely filling the width of said combustion chamber, an air blast
- jet beneath said vapor jet adapted to deliver a blast of air in substantially the same direction as said vapor jet, said heating 20 chamber having a plurality of exhaust-gas outlets arranged along the side wall thereof adjacent to the open end of said combustion chamber and beneath the latter and above the floor, and a reticulated partition between 25 said combustion chamber and said heating chamber and above said exhaust-gas outlets.
- Signed at New York city in the county of New York and State of New York this 22nd day of June A. D. 1914.

WILLIAM N. BEST.
